[57] CLAIM

The ornamental design for a banana bunch washing tray, as shown and described.

DESCRIPTION

FIG. 1 is an elevated perspective view of the banana bunch washing tray of this invention;

FIG. 2 is a side elevational view of the tray of FIG. 1 from the left side of FIG. 1. The opposite side view is identical;

FIG. 3 is an end elevational view of the tray of FIG. 1 taken from the right end of the FIG. 1. The opposite end view is identical;

FIG. 4 is a bottom plan view of the tray of FIG. 1;

FIG. 5 is a cross sectional view of the banana bunch washing tray of FIG. 1 taken along the lines V—V of FIG. 1; and,

FIG. 6 is an enlarged fragmentary cross sectional view taken along the lines VI—VI of FIG. 5.

FIG. 2

FIG. 3

FIG. 4

FIG. 5

FIG. 6
